UNITED STATES PATENT OFFICE.

GERTRUDE GERLINGER, OF MONTEBELLO, CALIFORNIA.

TABLE DECORATION.

Application filed February 16, 1926. Serial No. 88,532.

This invention relates to a table decoration. It has been customary heretofore, to decorate tables with flowers, placed in vases or bowls, and it has also been a common 5 custom to use candles set on the table for giving light during the meal. Such vases or bowls used for holding the flowers, are frequently ornamental and costly, and the candlesticks for the candles, if ornamental, are 10 also usually expensive.

The general object of this invention is to provide a very simple and inexpensive table decoration which will operate as a holder for flowers and for a candle or candles.

15 According to my invention, I provide a simple device which may be constructed of wire for a few cents but which will operate to hold a loose fibrous material such as moss so that the wires of the frame or holder 20 will be concealed; and I also provide the frame with a candle-holder which is preferably attached to the bottom of the moss-holder and in such a way that the candle-holder may also be concealed by the moss. 25 While the fibrous material or the moss itself may be ornamental, it also from its nature enables the stems of the flowers to be readily stuck into it; in this way a very attractive and ornamental floral and candle-light effect is attained.

30 Further objects of the invention will appear hereinafter.

The invention consists of the novel parts and combination of parts to be described 35 hereinafter, all of which contribute to produce an efficient table decoration.

A preferred embodiment of the invention is described in the following specification, while the scope of the invention is pointed 40 out in the appended claims.

In the drawing:

Figure 1 is a plan of a device embodying features of my invention.

Figure 2 is a vertical section through the 45 device shown in Figure 1 and also indicating the manner in which the fibrous substance, flowers and the candle are held by the device.

Figure 3 is a plan showing another embodiment of the invention.

Figure 4 is a vertical section taken on the line 4-4 of Figure 3 upon an enlarged scale, the body of the device being broken away.

95 In practicing the invention, I provide a holder for fibrous material. This material

may be artificial or natural, for example moss, vines or the like. The holder is preferably in the form of a light frame constructed of wire. To this frame, I attach 60 one or more candle holders preferably attached to the bottom of the frame, so that the candle carried in the holder may be completely surrounded by moss and flowers. The loose fibrous character of the moss enables it to be easily penetrated by the stems 65 of the flowers in completing the table decoration.

Referring to the embodiment of the invention, shown in Figures 1 and 2, the device consists of a light frame 1 which may be constructed of copper or galvanized iron wire. This frame, for convenience, is preferably of circular form and comprises a circular bottom wire 2, the opposite sides of 70 which are connected by a plurality of diametrically placed cross-bars 3, also of wire. The device also includes an upper circular wire 4 which is connected to the base or bottom wire 2 by a plurality of vertical wires 75 or standards 5. The points of contact of the different wires or elements of the device may be connected by solder or brazing. The bottom of the device may include an inner circular wire 6 of smaller diameter than the 80 bottom wire 2 and supported on the upper sides of the diametrically placed wires 3.

85 Preferably at the center of the bottom of this frame, I provide a candle-holder 7 which is preferably in the form of a light wire bent 90 into a coil of a suitable diameter to fit neatly around the shaft of a candle 8. The lower end of this coil may have an integral extension or foot 9, the end of which is soldered or brazed to one of the cross-wires at the point 95 10. The lowest convolution 11 of the coil 7 should also be secured by solder at several points, for example, the points 12 and 13, where it is in contact with the cross-wires. In using the device, I fill the frame or holder 100 1 with a loose fibrous material 14 which may be artificial or natural. It should be so placed that the frame and the candle holder are concealed. I prefer, however, to use natural moss or vines for this purpose, on 105 account of the fact that the same can be moistened. The moisture in the moss will operate to keep the flowers fresh. They may be stuck into the moss from above as illustrated in Figure 2. It should be understood that the moss is preferably not tightly 110 packed, but should be loose enough so that

the stems of the flowers may be readily thrust down into it.

In this way, a very attractive table decoration results and an ornamental effect will be attained, even if very few flowers are employed, although the best effect is attained when the flowers are thickly applied so as to give the effect of a bouquet from the center of which the candle projects. The candle 10 extends up through the interior of the frame.

In Figures 3 and 4, I illustrate another embodiment of the invention in which the effect of a relatively large table decoration 15 is attained without a great increase in the quantity of flowers and moss. In this embodiment of the invention, the frame 15 of the device is of annular form and composed of two upper wires 16 and 17 of circular 20 form which are disposed at about the same level. At a plurality of points around the device, these upper wires 16 and 17 are connected together by frame wires 18 which extend downwardly and attach at their middle 25 points to a bottom wire or base wire 19 which is also of circular form and of a diameter intermediate between the diameter of the wires or rings 16 and 17.

At a plurality of points around the frame, 30 I provide candle holders 20 which may be in the form of coils of wire similar to the coil 7.

In using this device, the frame 15 will be filled with moss or vines applied so as to con-

ceal the frame and so as to afford a support for flowers which may be applied as indicated in Figure 2.

If desired the moss may be used in a very moist state, in which case a plate should be placed under the decoration to prevent 40 the moisture from wetting the table cloth.

What I claim is:

1. A table decoration consisting of a holder formed of wire and operating to hold moss or the like, and a candle-holder attached to the moss-holder and disposed within the same so that the candle-holder is surrounded by the moss held in the moss-holder. 45

2. A table decoration consisting of a moss-holder formed of wire having a candle-holder 50 formed of wire attached on the interior of the same in a position to be concealed by the moss held in the holder.

3. A table decoration consisting of a moss-holder of circular form, composed of wire 55 and having a bottom with a candle-holder attached to the bottom and extending up through the interior of the moss-holder.

4. A table decoration consisting of a light frame composed of wire and having a 60 candle-holder attached thereto, and a loose fibrous material received in the frame, concealing the candle-holder and frame and operating to receive and support the stems of flowers. 65

Signed at Los Angeles, California, this 8 day of February, 1926.

GERTRUDE GERLINGER.
